CLAIM

The ornamental design for electrical connector housing with asymmetric rectangular hot terminal edge slots, as shown and described.

DESCRIPTION

FIG. 1 is a top, side perspective view of an electrical connector housing with asymmetric rectangular hot terminal edge slots showing our design;

FIG. 2–FIG. 5 are different side views thereof;

FIG. 6 is a top view thereof; and,

FIG. 7 is a bottom view thereof.

In FIG. 6, the circular broken line feature shows a portion of an electrical connector housing with asymmetric rectangular hot terminal edge slots that forms no part of the claim.
